UNITED STATES PATENT OFFICE

101,288

DESIGN FOR A COMBINED WALL LIGHTER AND THERMOMETER

Willis Jay Richardson, Dallas, Tex.

Application June 5, 1936, Serial No. 63,048

Term of patent 7 years

To all whom it may concern:

Be it known that I, Willis Jay Richardson, a citizen of the United States, residing at Dallas, in the county of Dallas and State of Texas, have invented a new, original, and ornamental Design for a Combined Wall Lighter and Thermometer, of which the following is a specification, reference being had to the accompanying drawing, forming part thereof.

Figure 1 is a view in front elevation of a combined wall lighter and thermometer, showing my new design.

Figure 2 is a view in side elevation thereof.

I claim:—

The ornamental design for a combined wall lighter and thermometer as shown.

W. J. RICHARDSON.
